(57) **CLAIM**

The ornamental design for a “extending cookware handle with open end cavity,” as shown and described.

DESCRIPTION

FIG. 1 is a perspective view of the “extending cookware handle with open end cavity” showing my new design;
FIG. 2 is a right side elevation view thereof, the left side elevational view thereof, the left side elevation view being a mirror image thereof;

FIG. 3 is a top plan view thereof;

FIG. 4 is a bottom plan view thereof;

FIG. 5 is a front elevation thereof;

FIG. 6 is a back elevation view thereof;

FIG. 7 is a partial cross-sectional view of the terminal portion of the handle taken along the line 7-7 from FIG. 3;

FIG. 8 is a perspective view of a second embodiment of the “extending cookware handle with open end cavity” showing my new design;

FIG. 9 is a right elevation view thereof, the left side elevational view being a mirror image thereof.

FIG. 10 is a top plan view thereof;

FIG. 11 is a bottom plan view thereof;

FIG. 12 is a front elevation thereof;

FIG. 13 is a back elevation view thereof; and,

FIG. 14 is a partial cross-section view of the terminal portion of the handle taken along the line 14-14 from FIG. 10.

The broken lines in FIGS. 1,5,6,8,12 and 13 are for illustrative purposes only, depicting the environment of the new design, forming no part thereof as claimed.
